UNITED STATES PATENT OFFICE.

HENRY DARBY, OF LONDON, ENGLAND, ASSIGNOR TO WILLIAM CHARLES PUNCHARD, OF SAME PLACE.

CIRCULAR-FLAME GAS-BURNER.

SPECIFICATION forming part of Letters Patent No. 650,306, dated May 22, 1900.

Application filed August 31, 1899. Serial No. 729,104. (No model.)

To all whom it may concern:

Be it known that I, HENRY DARBY, manufacturer, a subject of the Queen of Great Britain, residing at 249 Pentonville road, King's 5 Cross, London, England, have invented certain new and useful Improvements in or Relating to Circular-Flame Gas-Burners, of which the following is a specification.

This invention relates to circular-flame gas-burners, novel and striking effects being produced according to the present invention, the flame having very much the appearance of the present well-known incandescent gas-burner with mantle, although no Bunsen 10 burner is employed and no mantle is used or intended to be used according to the present invention, an incandescent-like mantleless gas-burner being thus produced.

Referring to the accompanying drawings, 15 in which the present invention is illustrated, Figure 1 is an exterior view, in side elevation, of the gas-burner of circular form constructed according to the present invention. Fig. 2 is a vertical sectional view taken through the 20 middle of this circular burner—*i. e.*, on line 2 2, Fig. 1. Fig. 3 is a horizontal cross-sectional view on line 3 3, Fig. 2; and Fig. 4 is a similar view on line 4 4, Fig. 2, looking downward in both cases.

Similar letters of reference indicate corresponding parts throughout.

A is a gas-inlet pipe, to which the supply of gas is led in any suitable manner. For instance, the lower end of said pipe A may be 25 screwed or otherwise attached to any ordinary gas bracket or chandelier, &c.

A' are branch pipes (as in ordinary and well-known Argand burners) by which the gas is supplied to an ordinary Argand circular 30 gas-burner B.

C is an ordinary "basket" or restrictor of any suitable character which extends from a horizontal plane about three-quarters of an inch below the top of the Argand burner B 35 downward and inward in a conoidal or tapering form, as shown, and terminates at a point about two and one-half to three inches below the top edge of said burner B. (See Fig. 2.)

D is a horizontal flat rim or ring with downwardly-extending flange D', within which latter the basket C fits and is there held in po-

sition by any suitable means, such as the nut C' and washer C'', (see Fig. 2,) and E E are three (or other suitable number of) inwardly-extending arms which carry the central collar or burner-mount F, which latter is thus supported concentrically within the restrictor, &c., and this collar F is internally screw-threaded and adapted to have screwed thereinto the metal part B' of the Argand 60 burner B, which latter is exteriorly screw-threaded for this purpose, whereby said flanged ring or rim D and restrictor C and burner B are thus firmly and concentrically secured together. 65

H is a cone or hood which is mounted concentrically with the Argand burner B and secured to the upper side of the said rim or mount D at a point a little outside of the projecting inner edge D' (the object of which 70 latter is hereinafter described) of said mount D, and as said hood extends upwardly it contracts until above the top edge of the burner B, and then said hood is flared or widened out and terminates at a point about three-quarters or seven-eighths of an inch above the top of the burner B. (See Fig. 2.) At the lower part of said hood H there is a clear annular space between the exterior of the burner B and the inside of said hood H, which 75 latter, at or near the bottom edge thereof, is provided with a series of apertures H', leading into an annular inclosed air-heating chamber X, formed between the outer side of the lower part of the hood H and the jacket I, 80 which latter is provided with a series of outlet-apertures I', located within the interior diameter of the chimney Y, so that when the latter (which is to be a straight chimney) is mounted in position in the chimney-gallery 85 K a supply of heated air will thus be led through the outlets I' from the annular chamber X in between the inside wall of the glass or other chimney Y and the exterior of the upper part of the hood H, and such supply 90 of heated air is caused to impinge on the exterior of the flame just as same rises above the top edge of the hood H. 95

M is a vertical central post fixed in or to the Argand burner, and mounted on said support M is the button or "flame-spreader" N, which latter is located and supported exactly 100

level, or thereabout, with the top edge of the hood H, as shown in Fig. 2.

In Fig. 2 the approximate shape the flame assumes in burning is shown in dotted lines, (marked Z.)

The inwardly-projecting edge D², Fig. 2, limits the amount of air which can thus pass upward through the space between said inner edge D² and the exterior of the burner B, whereby the air-supply at this point is limited and regulated, and thereby greatly assists in producing steadiness in the flame. It will thus be seen that the air-supply entering through the basket or restrictor C is led to the flame by three separate annular passages, namely: first, a supply of air is led to the interior of the flame through the central annular passage a, formed inside the burner B, between the post M and the inside wall of said burner B; second, a supply of air passes up through the annular passage b, formed between the outside of the burner B and the inside of the lower part of the hood H, and, third, the supply of heated air coming from the annular heating-chamber X through the annular space c, formed between the outside of the upper part of the hood H and the inside of the lower part of the chimney Y, impinges on the outside of the flame as the latter emerges above the top of the hood H. Upon lighting the gas coming from the Argand burner B these several air-currents acting in conjunction with the special shape of the hood H and the arrangement of the latter in juxtaposition to the burner B cause the flame to produce a brilliant light, while the spreader N, acting in conjunction with the hood and arrangement of air-currents, causes the flame to assume a somewhat conical or conoidal form, as indicated by the dotted lines Z in Fig. 2, and the flame thus has very much the appearance of the well-known incandescent gas-burner with mantle, and this effect may be further heightened by having the lower part of the chimney Y perfectly transparent from the bottom up to about line y y, and above this line y y the glass or chimney may be made semitransparent or translucent or even opaque, so that the topmost part of the flame Z is hidden by said non-transparent part of the chimney Y above the line y y.

Having now described my invention, what I claim as new, and desire to secure by Letters Patent of the United States, is—

55. 1. The combination with an Argand burner, of a hood or cone concentrically arranged around the upper part of said burner and extending above the top edge thereof, a button or flame-spreader—supported centrally within said hood—on a level with the top edge of said hood, a basket or restrictor C arranged concentrically below said hood an annular inwardly-projecting edge D² arranged below the top edge of the burner to limit and regulate the air-supply at this point, and means to admit a supply of air to the passage c between the exterior of the hood and the in-

terior of the chimney Y which latter air-supply impinges on the exterior of the flame as it rises above the top edge of the hood, substantially as and for the purposes set forth. 70

2. The combination with an Argand burner, of a hood or cone concentrically arranged around the upper part of said burner and extending above the top edge thereof and an annular air-heating chamber X formed around the exterior of the hood to heat the air-supply to the passage c exterior of the hood which latter air-supply impinges on the exterior of the flame as it rises above the top edge of the hood, substantially as and for the purposes set forth. 80

3. The combination with an Argand burner of a hood or cone concentrically arranged around the upper part of said burner and extending above the top edge thereof, an inwardly-projecting edge D² arranged below the top edge of the burner to limit and regulate the air-supply on its way to the exterior of the flame and an annular air-heating chamber X formed around the exterior of the hood to heat the air-supply to the annular passage c exterior of the hood which latter air-supply impinges on the exterior of the flame as it rises above the top edge of the hood, substantially as and for the purposes set forth. 90

4. The combination with an Argand burner of a hood or cone concentrically arranged around the upper part of said burner and extending above the top edge thereof, a basket or restrictor C arranged concentrically below said hood, an inwardly-projecting edge D² arranged below the top edge of the burner to limit and regulate the air-supply on its way to the exterior of the flame, and an annular air-heating chamber X formed around the exterior of the hood to heat the air-supply to the passage c exterior of the hood which latter air-supply impinges on the exterior of the flame as it rises above the top edge of the hood, substantially as and for the purposes set forth. 100

5. The combination with an Argand burner of a hood or cone concentrically arranged around the upper part of said burner and extending above the top edge thereof, a basket or restrictor C arranged concentrically below said hood, an inwardly-projecting edge D² arranged below the top edge of the burner to limit and regulate the air-supply on its way to the exterior of the flame, and an annular air-heating chamber X formed around the exterior of the hood to heat the air-supply to the passage c exterior of the hood which latter air-supply impinges on the exterior of the flame as it rises above the top edge of the hood, substantially as and for the purposes set forth. 110

6. The combination with an Argand burner, of a hood or cone concentrically arranged around the upper part of said burner and extending above the top edge thereof and an annular air-heating chamber X formed around the exterior of the hood to heat the air-supply to the passage c exterior of the hood which

latter air-supply impinges on the exterior of the flame as it rises above the top edge of the hood, substantially as and for the purposes set forth.

- 5 7. The combination with an Argand burner of a hood or cone concentrically arranged around the upper part of said burner and extending above the top edge thereof, an inwardly-projecting edge D^2 arranged below the top edge of the burner to limit and regulate the air-supply on its way to the exterior of the flame and an annular air-heating chamber X formed around the exterior of the hood to heat the air-supply to the annular passage c exterior of the hood which latter air-supply impinges on the exterior of the flame as it rises above the top edge of hood substantially as and for the purposes set forth.

- 15 8. The combination with an Argand burner of a hood or cone concentrically arranged around the upper part of said burner and extending above the top edge thereof, a button or flame-spreader N supported centrally within said hood on a level with the top edge of said hood, a basket or restrictor C arranged concentrically below said hood, an inwardly-projecting edge D^2 arranged below the top edge of the burner to limit and regulate the air-supply on its way to the exterior of the flame, and an annular heating-chamber X formed around the exterior of the hood to heat the air-supply to the passage c exterior of the hood which latter air-supply impinges on the exterior of the flame as it rises above the top edge of the hood, substantially as and for the purposes set forth.

- 25 9. The combination with an Argand burner of a central collar F adapted to have said burner screwed therein, arms E on ring D supporting said collar, a restrictor C butting with said ring D and held in position by a nut on the gas-inlet pipe leading to said burner, an inwardly-projecting edge D^2 on said ring D , a hood H mounted on the upper side of said ring D and extending above the top of the burner, an annular jacket I mounted exteriorly of said hood H and forming an annular air-heating chamber X , air-admission openings H' leading through the lower part of said hood H into said chamber X , and a series of outlet-openings I' leading from said chamber X into the space c between the interior of the chimney Y and the exterior of the upper part of the hood H , substantially as and for the purposes set forth.

10. The combination with an Argand burner of a central collar F adapted to have said burner screwed therein, arms E on ring D supporting said collar, a restrictor C butting with said ring D and held in position by a nut on the gas-inlet pipe leading to said burner, an inwardly-projecting edge D^2 on said ring D , a hood H mounted on the upper side of said ring and extending above the top of the burner, a button or flame-spreader N supported centrally within said hood on a level with the top edge of said hood, an annular jacket I mounted exteriorly of said hood H and forming an annular air-heating chamber X , air-admission openings H' leading through the lower part of said hood H into said chamber X , and a series of outlet-openings I' leading from said chamber X into the space c between the interior of the chimney Y and the exterior of the upper part of the hood H , substantially as and for the purposes set forth.

11. The combination with an Argand burner, of a hood or cone concentrically arranged around the upper part of said burner and extending above the top edge thereof, a basket or restrictor C arranged concentrically below said hood or ring D' having a peripheral flange fitting over said basket or restrictor, and an inwardly-projecting edge D^2 extending within said hood and arranged concentric to the burner but spaced therefrom, below the top edge of the burner to limit and regulate the air-supply on its way to the exterior of the flame, substantially as and for the purposes set forth.

12. The combination with an Argand burner, of a hood or cone concentrically arranged upon the upper part of said burner and extending above the top edge thereof, and a jacket I having restricted passages, surrounding said hood and forming an annular air-heating chamber X around the exterior of the hood for heating the air-supply to the exterior of the hood, which air-supply impinges on the exterior of the flame as it rises above the top edge of the hood, substantially as and for the purposes set forth.

In witness whereof I have hereunto set my hand in presence of two witnesses.

HENRY DARBY.
